UNITED STATES PATENT OFFICE

EDWARD R. SMITH, OF NEW CASTLE, PENNSYLVANIA

EDUCATIONAL DEVICE

Application filed February 4, 1928. Serial No. 251,784.

Figure 1 is a front view of the device.

Fig. 2 is a view of the rear of the device.

Fig. 3 is a view of the rear of the device, the upper portion of the case being removed to show the interior.

Fig. 4 is a front elevation of the device, certain parts being shown as broken away to disclose the interior of the device, and other parts being indicated in dotted lines.

Fig. 5 is a side elevation of the device, the casing end being removed, and

Fig. 6 and Fig. 7 are fragmentary views of the operating disks.

This invention relates to educational devices and more particularly to a device adapted for use in the instruction of shorthand and typewriting.

The main object of this invention is the provision of an educational device which will intermittently and periodically expose suitable characters such as letters, combinations of letters, and figures to the eye of a student whereby to enable him to gain speed in either typing the characters or in writing the same stenographically.

Another important object of the present invention is to provide a drive mechanism for the educational device that includes drive and driven discs, the driven disc having educational indicia on the front face thereof and which indicia is adapted to be displayed to view in such a manner whereby the character change is made substantially instantaneously and the exposed character or indicia remains in view a relatively considerable length of time.

Other objects and advantages of this invention will be apparent from the following description taken with the accompanying drawings in which the device is shown as comprising a casing designated generally as A which is shown as substantially clock shape although this is merely by way of example as obviously casings of other and desired shapes may be employed within the spirit of the invention.

The casing A includes a bottom 2 supported and preferably attached to a suitable support or base 4, a rear wall 6 and a front wall or cover 8 hingedly connected as at 10 to the

side wall 12. The front wall or cover is provided with a sight opening 14 and shutters 16 and 18 are hingedly secured to the cover 8 by vertical pintle extending vertically and centrally of the opening 14 as shown at 20 for the purpose of closing either half of the sight opening as desired. This arrangement of double shutters hinged to close different portions of the opening as desired, permits various combinations of indicia, hereinafter described, to be exposed. For convenience, the device is provided with a handle shown at 22.

The rear wall is provided with an opening which is normally closed by a plate 24 provided with a knob 26 for an obvious purpose.

The interior of the casing contains the mechanism now to be described, and as clearly shown in Fig. 5, a bracket 26 is bolted or otherwise secured to the base 2; the bracket having a bearing 28 at its upper end which rotatably supports a shaft 30 to the rear end of which is secured a relatively large gear 32 which is in mesh with a pinion 34 rotatably secured or mounted upon a stub shaft 36 carried in a journal 38 secured to or formed with the bracket 26. The pinion is secured against displacement on the shaft by any suitable means such as a nut 40 or the like and is in mesh with a small gear 42 driven by a suitable motor 44 secured to the base 2 by bolts 46 or the like. In the present instance an electric motor is shown as the driving medium for the gearing 42, 34 and 32, but this is merely by way of example as obviously other driving means might be employed within the spirit and scope of the invention, and it is not to be understood that the present invention is limited or restricted to the use of an electric motor. For example, a spring motor or conventional type might be employed, if desired, but inasmuch as the particular construction of the driving means forms no specific part of the present invention the same is not shown in detail.

The forward end of the shaft 30 is reduced as at 48 to define a bearing shoulder 50 against which is positioned a circumferentially toothed disk 52, the teeth of which are generally cam shaped as shown clearly in Fig. 100

6 providing a curved or arcuate surface 54 and a straight surface 56 between adjacent teeth. This disk is securely attached to the shaft 30 in any suitable manner whereby to be continuously rotated thereby.

5 A second disk designated as 58 is provided; the same being likewise circumferentially toothed. This disk I term the driven disk in contradistinction to the driving disk 52, and 10 the same is loosely mounted on the reduced end 48 of the shaft 30 so as to be capable of relative rotation therewith. The disk 58 is resiliently connected to the driving disk 52 by a coil spring 60 the ends of which are secured 15 to the disks 52 and 58 as shown at 62 and 64 respectively. The teeth of disk 58 are similar to the teeth of disk 52, but, as can be clearly seen in Figs. 6 and 7, are pitched opposite to the pitch of the teeth of disk 52 for a purpose 20 to be presently described.

Secured to the base 2 on a support 66 is a spring retainer 68 the free end of which is bent upwardly to form a catch element 70 which normally extends between adjacent 25 teeth of disks 52 and 58. This arrangement is such as to retain the disk 58 against rotation until catch element 70 is released from engagement therewith as now described.

Removably secured to the disk 58 by means 30 of small screws 71 or other like attaching elements is a disk 72 which I term a lesson disk; the same being formed of paper, cardboard, or light sheet metal and provided with circumferentially arranged series of characters 35 such as letters, figures or the like adjacent the marginal edge thereof whereby they may be exposed through the sight opening 14 heretofore mentioned.

In practice a plurality of disks 72 are provided, each having a different series of characters thereon, or the same characters arranged in different sequences, it being understood of course, that the disks 72 are interchangeable by removing the small screws or other attaching elements 71. For retaining 40 the disk 58 and its associated lesson disk 72 on the shaft 30, any suitable means may be employed, but in the instance shown, a nut 75 is provided which engages the reduced end of 45 shaft 30.

50 In the operation of the device, when the motor is started the shaft 30 is rotated, thus rotating disk 52. The catch element 70 is positioned between adjacent teeth of each of the disks 52 and 58, and retains the disk 58 against rotational movement relative to the shaft 30, as will be apparent. The rotation of disk 52 will cause the cam surfaces of the teeth of said disk 52 to successively engage 55 the catch element 70 and depress the same to free it from its engagement with the teeth of disk 58 and the latter will be intermittently rotated; the catch element periodically and intermittently engaging the teeth of disk 58 60 successively to restrain the disk 58 against

rotation while so engaged. Periodic and intermittent rotation of the disk 58 will successively expose the characters on the lesson disk through the sight opening 14 as will be obvious.

70 In addition to the before mentioned series of characters, an additional series of characters indicated at 83 may be used or applied to the lesson disks; this series 83 being of larger size than the before mentioned series 75 and being especially adapted for beginners in the study of shorthand or typewriting. In order to expose these characters to view, an additional sight opening 84 may be provided or formed in the cover 8; similar to the 80 sight opening 14.

As is usual with motors generally, this invention contemplates the use of a governor for controlling the speed of the motor and consequently varying the speed of rotation 85 of disk 52 and the intermittent rotation of disk 58; but inasmuch as the specific construction of the governor forms no part of the present invention, the same is not shown, it being understood that any conventional 90 governor may be employed.

95 From the above description, it is believed that the invention will be fully apparent to those skilled in the art to which it appertains but I desire it understood that various changes in the form and proportions of the device may be made within the spirit of the invention without departing from the spirit of the invention or the scope of the appended 100 claims.

100 What I claim is:

1. In an educational device of the class described, a casing, a driving disc mounted therein, a driven disc therein, resilient connecting means between said discs whereby the driven disc is adapted for rotation upon the rotation of the driving disc, educational indicia on said driven disc, said casing having an opening therein for the observation therethrough of the indicia on said driven disc, 110 means for actuating said driving disc, cam-like teeth formed on the peripheral edges of said discs, the teeth of said discs being respectively pitched oppositely, yielding means engaging the teeth on said driven disc to restrain the rotation of the latter for a predetermined length of time, the teeth of the driving disc contacting with said yielding means at predetermined intervals for releasing the engagement thereof with the teeth of said 115 driven disc to permit a predetermined rotational movement of the latter, whereby the character change is made substantially instantaneously and the exposed character remains in view a relatively considerable length 120 of time.

125 2. In a drive mechanism for an educational device of the class described, a rotatable shaft, a driving disc fixedly secured thereon, a driven disc loosely mounted on said shaft 130

in slight spaced relation with respect to the driving disc, said driven disc being adapted to carry characters on the front face thereof, a coil spring encircling the shaft and interposed between said discs, one end of said spring being connected to the driving disc, the other end being connected to the driven disc, said coil spring providing a resilient connection between the discs whereby the driven disc will be adapted for rotation upon the rotation of the driving disc, cam-like teeth formed on the peripheral edges of said discs, all of the teeth of one disc being pitched in one direction, all of the teeth of the other disc being pitched in the other direction, a spring pawl engaging the teeth on the driven disc to prevent rotation of the latter for a predetermined length of time, the teeth of the driving disc contacting with said pawl at predetermined intervals for releasing the engagement thereof with the teeth of the driven disc to permit a predetermined rotational movement of the latter whereby the character change is made substantially instantaneously and the exposed character remains in view a relatively considerable length of time.

In witness whereof I have hereunto set my hand.

EDWARD R. SMITH.
